SWITCH AND SIGNAL COMPANY, OF SWISSVALE, PENNSYLVANIA, A CORPORATION
OF PENNSYLVANIA.

ELECTRIC SIGNALING SYSTEM.

964,710.

Specification of Letters Patent. Patented July 19, 1910.

Application filed April 28, 1908. Serial No. 429,587.

To all whom it may concern:

Be it known that I, JOHN D. TAYLOR, of Edgewood Park, Allegheny county, Pennsylvania, have invented a new and useful 5 Electric Signaling System, of which the following is a full, clear, and exact description, reference being had to the accompanying drawing, in which the figure is a diagrammatic view illustrating one embodiment of my invention.

My invention has relation to block signaling systems which are especially adapted for use on railroads in which electric propulsion is employed, and to that class of these 15 signals in which the track rails, instead of being divided into insulated sections or blocks, are electrically continuous for the propulsion current. In systems of this kind which have heretofore been proposed, the 20 block limits have necessarily been more or less indeterminate, due to the fact that in such systems the relays which control the signals are operated to set the signals at danger by the short-circuiting action of the trains; and that the precise points at which this short-circuiting occurs in many cases 25 frequently varies on account of weather and other conditions so that there are no precise limits separating one block from another.

30 It will be understood that the term "block" as used herein does not have its usual signification of an electrically independent section of the track rails, but that it is used for convenience to designate those 35 portions of the track which are located between adjacent signals.

The object of my invention is to provide 40 means of simple and effective character whereby the block limits may be more closely and certainly defined, and the broadly novel feature of my invention consists in the provision of means whereby the signal-controlling relays are operated by means of currents induced by the signaling currents. 45 Inasmuch as the portions of the track where these induced relay operating currents are generated can be closely limited, means are thus provided for positively controlling the 50 operation of the relays and for determining the block limits.

The precise nature of my invention will 55 be best understood by reference to the accompanying diagram, in which I have shown one embodiment thereof, and which will now be described, it being premised, how-

ever, that various changes may be made therein by those skilled in the art without departing from the spirit and scope of my invention as defined in the appended claims.

In this diagram, the letter A designates a 60 generator for supplying the propulsion current, and which may be either a direct generator or an alternator. One terminal of this generator is connected to the usual third rail or trolley wire *h*, and the other terminal 65 is connected with conductor *m*, which connects the two rails of the track.

B is an alternating current generator for 70 supplying the signaling current, and should be adapted to give a current of considerably higher frequency than the generator A where the latter is an alternator. The current from the generator B is led to the various signaling instruments by means of the line wires *j*, *k*. 75

C, C', are transformers, whose primary coils *p*, *p'*, are connected across the line wires *j*, *k*, and whose secondary coils *s*, *s'*, are connected to the track rails *r*, *r'* at points which are as nearly as may be at the middle of the 80 respective blocks which the transformers supply with current. The rails *r*, *r'* are electrically continuous for the propulsion current.

Opposite points of the two rails marking 85 approximately the ends of the respective blocks are joined by transverse conductors *m*, *m'*, *m''*, etc., these cross-connections forming closed circuits for the currents induced in the secondary coils of the transformer; that is, the current from any secondary coil will flow through the rail *r* to the adjacent cross conductors to the rail *r'*, and back to the transformer. These cross-connections further serve to balance the 90 propulsion current flowing in the track rails. The currents flowing in these closed circuits will produce a magnetic flux around each rail; and if a loop of wire or other conductor, of which the cross-conductor may 100 form a part, is so placed as to be included within the lines of force of this flux, the conductor will have induced in it an electro-motive force which may be utilized to produce a current for operating the signal-controlling relays. 105

R, R', R'', R''', etc., designate these signal controlling relays. In the arrangement shown they consist each of two elements, the field elements *f*, *f'*, etc., being connected 110

across the line conductors j , k , and the armature elements a , a' , etc., being connected in a circuit formed by conductors g , g' which extend parallel with and adjacent to the track rails. The circuits for these armature elements of the relays may be traced on the diagram as being from the terminal of the armature a through the conductor g , the adjacent cross-conductor m' , thence back to the other terminal of the armature a . The circuit of the armature a' is formed in a similar manner by the other loop g' of the conductor, each pair of adjacent relays being on opposite sides of one of the cross-conductors, and utilizing such cross-conductor as a common part of their circuits. Two relays are provided for each block section, said relays having the contacts of the local signal circuit which they control in series with each other.

S , S' , designate signals for guarding the respective blocks, these signals being arranged to go to danger in the usual manner upon the opening of their controlling circuits.

T is a conventional representation of a train, which is shown as between the signals S , S' and between the relay R' and its transformer C' . As will be seen, this train shunts the current from the transformer secondary from those portions of the track rails to which the loop g' is adjacent. There will therefore be no flux through this coil and no current induced in it so long as the train occupies this portion of the block. The relay governed by said loop will therefore open its contacts and cause the signal to go to danger position. When the train passes the conductor m' , it will begin to cut out the flux passing through the loop formed by the wire g and will, when it arrives at some point between m' and g , cut out sufficient of this flux so that there will not be enough remaining to provide sufficient current to energize the armature a of the relay r . When this occurs, the circuit of the signal S will be opened and this signal will assume the danger position. It will, therefore, be seen that when a train occupies any portion of any block, one of the relays of that block will have its armature deenergized so that the signal protecting the train will be held at danger; and that as the train enters the next succeeding block it will at once gain control of the signal guarding that block before it loses control of the signal in rear. In this manner, the train is at all times protected by a danger signal in the rear. Inasmuch as the loops g , g' , etc., can be confined to those portions of the track rails adjacent to the block limit, and as the corresponding relays will be short-circuited only at such times as the train is in position to shunt the current which causes the mag-

netic flux which induces the relay operating currents into these loops, the points at which the relays will be short-circuited can be very closely determined, and thus give a very definite point at which the signals should be set to danger.

Owing to the fact that the alternator B produces a current of higher frequency than the generator A , where that generator supplies alternating current, it will be seen that the relays can be so constructed as not to be affected by the propulsion current. It will also be seen that there can be no interference in the operation of different relays, since each relay is operated to clear the corresponding signal only by the current induced in its own induction loop.

It will be obvious that various changes may be made in my invention without departing from its essential features. Thus, various forms of relays may be employed; their field elements may be connected in the induction loops, and their armature elements across the line conductors j , k , and various other changes may be made.

I claim:—

1. In a block signaling system, rails which are electrically continuous for both propulsion and signaling current, conductors connecting said rails at points adjacent to the block limits, signal controlling relays, and conductors arranged in inductive relation to the track rails for operating said relays, said conductors being connected to the relays through the cross-connections between the track rails; substantially as described.

2. In combination with an electric railway the rails of which are electrically continuous for both propulsion and signaling currents, a plurality of block sections formed by cross-connecting conductors between the rails, signal controlling relays, and conductors arranged in inductive relation with the track rails, said conductors being connected to the relays through the cross-connections between the track rails.

3. In combination with a railway, both rails of which are electrically continuous, a plurality of block sections formed by cross-connecting conductors between the two lines of rails at points adjacent the desired block section limits, signal controlling relays, conductors for each block section arranged in close inductive relation with the track rails, and a controlling circuit for each relay including said conductors and a cross-connecting conductor.

In testimony whereof I have signed my name to this specification in the presence of two subscribed witnesses.

JOHN D. TAYLOR.
